RAILWAY DRAFT RIGGING

William J. Regan, Wilkinsburg, and Enoch George, Jr., Pittsburgh, Pa., assignors to The McConway & Torley Company, Pittsburgh, Pa., a corporation of Pennsylvania

Application March 5, 1928, Serial No. 259,202

8 Claims. (Cl. 213—69)

This invention relates to a railway draft rigging and particularly to means affording a flexible connection between a car coupler and a draft yoke of the horizontal type.

5 The principal object of the invention is to provide a construction permitting the coupler to swing laterally and which will enable a standard coupler to be substituted in an emergency for the special design of swinging coupler when the latter is not available.

10 The primary feature of the invention, generally stated, consists in employing a horizontal draft yoke between whose arms is interposed a bearing block to which the rear end of the car coupler is 15 pivotally connected so as to swing laterally, the bearing block being associated with the yoke so as to directly communicate draft forces thereto.

15 A further feature of the invention consists in interposing between the horizontally spaced arms 20 of a draft yoke, a bearing block which is pivotally connected to a car coupler, the block being removably mounted upon the yoke and being adapted to have shouldered engagement so as to communicate draft forces directly thereto and 25 the bearing block being adapted to transmit buffering forces to the cushioning device carried by the yoke.

Another feature of the invention consists in 30 interposing a bearing block between the horizontally spaced arms of the draft yoke and in pivotally connecting a car coupler to the bearing block by a pin in quadruple shear, the yoke and block having cooperating inclined shoulders whereby 35 draft forces are communicated to the yoke from the block, and the latter being formed with laterally projecting portions which engage the arms of the yoke to thereby support the block.

40 In the drawing illustrating preferred embodiments of the invention, the scope whereof is pointed out in the claims:

Figure 1 is a view, partly in plan and partly in horizontal section, of a draft rigging embodying the invention, portions of the coupler and yoke being broken away.

45 Figure 2 is a vertical central section of a construction shown in Figure 1, the pivot pin and a portion of the coupler being shown in elevation and a follower block of the well known Farlow type being illustrated in dot and dash lines in conjunction therewith.

50 Figure 3 is a front elevational view of the yoke and bearing block shown in Figure 1, the parts being in assembled relation.

55 Figure 4 is a plan view of a modified form of

draft rigging embodying the invention, portions of the coupler and yoke being omitted.

Figure 5 is a side elevation of the construction illustrated in Figure 4.

60 Figure 6 is a detail elevational view of a modified form of yoke ends or straps suitable for use with either of the forms of bearing blocks illustrated in the drawing.

65 Figure 7 is a plan view of the construction shown in Figure 6.

70 The draft yoke arms or straps in each of the forms of the invention illustrated in the drawing are of the horizontal type, that is to say, the arms are disposed in horizontal alignment and are spaced apart sufficiently to receive a cushioning unit between them in the well known way.

75 In the construction shown in Figures 1, 2 and 3, each of the arms 1 of the yoke 2 is fashioned on its inner side at the forward end with a lug or projection 3, whose rear face 4 is inclined or undercut to correspond with a cooperating bevelled shoulder or seat 5 formed on a bearing block 6 slidably mounted between the yoke arms; such construction preventing the forward ends 80 of the yoke arms 1 from spreading when subjected to draft forces. The yoke arms 1 preferably have key slots 7 of the usual form to receive a standard key (not shown) adapted to pass through the usual slot of a Farlow follower block 8; and the rear face of the bearing block 85 6 is preferably centrally recessed, as at 9, to accommodate the stud with which the follower block 8 is commonly provided at its forward end.

90 The car coupler 10 is pivotally connected to the bearing block 6 by means of a vertically disposed pin 11 which extends through the coupler and bearing block only and thus serves to communicate all draft forces from the coupler directly to the block. To insure a strong and efficient pivotal connection, the rear end of the stem 95 of the coupler 10 is bifurcated to afford vertically spaced apertured pivot lugs 12 which intermesh with correspondingly apertured spaced pivot lugs 13, 14 and 15 respectively formed on the forward end of the bearing block 6. The 100 pivot pin 11, which extends through the aligned apertures of the several lugs, may advantageously be of the headless type and be supported by a horizontally extending pin 16 projecting therethrough and through a suitably apertured boss 105 17 formed on the under surface of the bearing block. The rear ends of the pivot lugs 12 of the car coupler are curved cylindrically so as to have an extended area of contact against correspondingly curved seats 18 of the bearing block 110

6 in all positions of lateral displacement the 80
coupler may assume in service. As shown more
particularly in Figure 2, the parts are prefer-
ably formed so that a small amount of clear-
5 ance is allowed between the forward side of the
pivot pin 11 and the adjacent faces of the pivot
lugs 12 of the coupler, and also between the for-
ward curved face 19 of the bearing block pivot
lug 14 and the adjacent curved surface 20 of the
10 coupler, the pivot pin 11 thus being relieved of
the strain of buffing forces.

At its upper end the bearing block 6 is formed
with outwardly projecting portions 21 which ex-
15 tend over the corresponding arms 1 of the yoke
when the parts are in assembled relation, the
yoke thus serving to support the bearing block
and the latter in turn supporting the rear end
20 of the coupler shank 10. The yoke 2 may be sup-
ported and retained in assembled position on the
car by the usual key which passes through the
slots 7 of the yoke arms.

In assembling the device the bearing block is
25 inserted between the yoke arms from above and
brought into engagement with the inwardly pro-
jecting lugs 3 at the forward end of the yoke.
After the cushioning unit has been placed in posi-
30 tion between the yoke arms and the device, as
thus assembled, has been raised to its position
between the sills of the car, the coupler 10 may
be pivotally connected to the bearing block 6
by means of the pivot pin 11.

The car coupler 10, illustrated in Figures 4
and 5, is like that forming part of the mecha-
35 nism disclosed in Figures 1, 2 and 3, but the bear-
ing block 22 and the draft yoke 23 associated
therewith are of slightly modified construction.
In the construction shown in Figures 4 and 5 the
horizontally spaced arms 24 of the yoke are pro-
40 vided above and below near their forward ends
with vertically extending lugs 25 which overlap
neighboring parts of the bearing block 22 so as
to receive draft forces communicated from the
latter. The yoke arms 24 are also provided with
45 horizontally aligned key slots 26 adapted to re-
ceive a key so as to enable a standard coupler
to be connected to the draft yoke 23 in case a
coupler having the special form of shank 10 is
unavailable whenever repairs are required to be
50 made. It will be understood, of course, that when
a standard coupler is substituted for the special
coupler 10, the bearing block is temporarily dis-
pensed with.

In addition to being formed at its upper end
55 with lateral projections or flanges 27 projecting
over the yoke arms 24, the bearing block 22 is
provided at its lower end with an additional pair
of lateral projections 27 which extend under the
yoke arms, the block 22, when in assembled po-
60 sition, thereby being supported against vertical
movement in both directions. As in the case of
the construction described, the rear end of the
coupler stem 10 is pivotally connected to the
bearing block 22 by means of a pivot pin 11, the
coupler being fashioned with pivot lugs 12 and
65 the bearing block being formed with pivot lugs
13, 14 and 15 respectively, corresponding in form
and function to the similar parts shown in Fig-
ures 1, 2 and 3. The bearing block 22 may be
employed with any of the forms of the yoke
70 illustrated in the drawing, as the rear vertical-
ly extending portion thereof is curved, as indi-
cated at 28, so as to permit the block to be in-
serted between the yoke arms either from above
or below and then turned so as to assume proper
75 operative position. The remaining details of

construction of the modified form of the invention
shown in Figures 4 and 5 may be, and prefer-
ably are, the same as those embodied in the
preceding figures of the drawing and such de-
tails have therefore been identified by corre-
sponding reference numerals.

The form of yoke arm or strap 29 illustrated
in Figures 6 and 7 is adapted to be used with
either the bearing block 6 or the bearing block
22. Each yoke arm 29 is provided on its inner
85 face with a lug 30 for cooperating with the for-
ward face of the bearing block with which it is
employed, the said lug being intersected by a slot
31 adapted to receive a key permitting a coupler
90 of standard form to be connected to the yoke.
To the rear of the slot 31 each yoke arm 29 is also
preferably provided with a slot 32 to receive a key
such as is employed in case a follower of the
Farlow type is used. As shown, the rear face 33
95 of the lug 30 is inclined to cooperate with the
correspondingly bevelled face 5 of the bearing
block 6.

We claim:

1. In a railway draft rigging, the combination
100 with a yoke having a plurality of horizontally
spaced arms, of a car coupler having a stem, a
member operatively interposed between the yoke
and car coupler for permitting pivotal movement
105 of the latter, the said member being loosely mount-
ed on the yoke and being integrally formed
with oppositely disposed projections overlapping
the respective arms of the yoke to provide means
110 for supporting said member on said yoke, and
means pivotally connecting the coupler to the
said member, the latter having overlapping en-
gagement with the yoke so as directly to com-
municate draft forces thereto and being adapted
115 to communicate buffing forces to a cushioning
device adapted to be carried by said yoke.

2. A railway draft rigging involving a yoke
120 having a plurality of horizontally spaced arms,
a car coupler, a member carried by the yoke and
movable with respect thereto and having shoul-
dered engagement with the latter so as to com-
municate draft forces thereto, and a pin pivotally
125 connecting the coupler to said member, the said
member and the coupler having overlapping por-
tions through which the pin extends and whereby
the latter is placed in quadruple shear.

3. In a railway draft rigging, the combination
130 with a yoke having a plurality of horizontally
spaced arms, of a car coupler having a stem, a
member operatively interposed between the yoke
and coupler for permitting pivotal movement of
135 the latter, the said member having lateral pro-
jections which overlap the arms of the yoke so
as to support said member, and means pivotally
connecting the coupler to said member for trans-
mitting draft forces to the latter, the said mem-
ber being slidable with respect to said yoke arms.

4. A railway draft rigging involving a yoke hav-
140 ing a plurality of horizontally spaced arms, a car
coupler, a member operatively interposed between
the yoke and coupler for permitting pivotal move-
ment of the latter, and means pivotally connect-
ing the coupler to said member, said yoke and
145 said member having shouldered engagement per-
mitting draft forces to be communicated to the
yoke and the said member being integrally pro-
vided with laterally projecting portions which
engage the arms of the yoke to support said mem-
ber.

5. In a railway draft rigging, the combination
150 with a yoke having spaced arms in horizontal
alignment, of a coupler having a stem, a member

- detachably carried by said arms and operatively interposed between the yoke and coupler and slideable rearwardly with respect to the yoke in buffing, said member and said yoke being provided with overlapping shoulders serving as means for communicating draft forces from said member to the yoke, and means pivotally connecting the coupler to the said member for directly transmitting draft forces to the latter.
6. A railway draft rigging involving a yoke having horizontally aligned spaced arms, a car coupler having a stem, a member carried by the yoke and slideable rearwardly with respect thereto in buffing, said member being interposed between said arms and being supported thereby, and means passing through and pivotally connecting said stem to said member, said yoke and said member having overlapping shoulders adapted to engage each other during draft movement of said coupler to transmit draft forces to the yoke.
7. In railway draft rigging, the combination of a coupler, a yoke, and means for connecting
- 5 said yoke and coupler, said means including a bearing block slideable relative to said yoke and non-rotatively engageable with said yoke for transmittal of draft forces, and means for pivotally securing said coupler to said block.
8. In coupler mechanism, the combination of a yoke having bearing members disposed thereon, a coupler associated with said yoke and movable with respect thereto, a bearing member pivotally connected to said coupler and movable therewith with respect to said yoke, means on said yoke for preventing movement of said bearing member other than translation, said bearing member and coupler having complementary bearing faces engageable over a substantially constant area regardless of the relative position of said coupler and yoke, said bearing member having members non-rotatively engaging said first named bearing members for transmitting draft stresses to said yoke.
